(57) **CLAIM**

The ornamental design for a paint shield, as shown and described.

DESCRIPTION

FIG. 1 is an isometric view of a paint shield, embodying my new design

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof; and,

FIG. 7 is a left side elevation view thereof.

The broken line showings of the hooks are provided for purposes of environment and form no part of the claimed design.
